DESIGN FOR A BASIN

Cecil W. Farrar, Buffalo, N. Y.

Application April 1, 1932. Serial No. 43,355

Term of patent 14 years

To all whom it may concern:

Be it known that I, CECIL W. FARRAR, a citizen of the United States, residing at Buffalo, in the county of Erie and State of New York, have invented a new, original, and ornamental Design for a Basin, of which the following is a specification, reference being had to the accompanying drawing forming part hereof:

In said drawing—

Fig. 2 is a top plan view thereof.

I claim:
The ornamental design for a basin, as shown.
In witness whereof, I have hereunto subscribed my name.

CECIL W. FARRAR.
